(57) **CLAIM**

The ornamental design for a wireless charging bracket, as shown and described.

DESCRIPTION

1. Wireless charging bracket

1.1: Front

1.2: Back

1.3: Left

1.4: Right

1.5: Top

1.6: Bottom

1.7: Perspective

1.1 is a front view of a wireless charging bracket showing my new design;

1.2 is a back view thereof;

1.3 is a left view thereof;

1.4 is a right view thereof;

1.5 is a top view thereof;

1.6 is a bottom view thereof; and

1.7 is a perspective view thereof.

The broken line circle shown in 1.2, and the areas encompassed within, illustrate portions of the wireless charging bracket that form no part of the claimed design.

1 Claim, 7 Drawing Sheets
